UNITED STATES PATENT OFFICE

153,866

DESIGN FOR A SELF-CONTAINED REFRIGERATION UNIT

Ernest W. Ekstrand, Orange, N. J., assignor to
Ekstrand Manufacturing Company, Orange,
N. J., a corporation of New Jersey

Application April 16, 1947, Serial No. 138,426

Term of patent 14 years

(Cl. D67—3)

To all whom it may concern:

Be it known, that I, Ernest W. Ekstrand, a citizen of the United States, residing at Orange, in the county of Essex and State of New Jersey, have invented a new, original, and ornamental Design for Self-Contained Refrigeration Unit, of which the following is a specification, reference being had to the accompanying drawing, forming a part thereof:

Fig. 1 is a top plan view of a self-contained refrigeration unit showing my new design;

Fig. 2 is a side elevation; and

Fig. 3 is a perspective view thereof.

The unexposed side of the unit is substantially like the side illustrated in the drawing.

I claim:

The ornamental design for a self-contained refrigeration unit, as shown and described.

ERNEST W. EKSTRAND.
